UNITED STATES PATENT OFFICE.

JOHN P. BALL, OF CHICAGO, ILLINOIS.

BREAKWATER-WALL CONSTRUCTION.

Application filed December 13, 1922. Serial No. 606,663.

To all whom it may concern:

Be it known that I, JOHN P. BALL, a citizen of United States, residing in the city of Chicago, in the county of Cook and State 5 of Illinois, United States of America, have invented a new and useful Improvement in Breakwater-Wall Construction, of which the following is a specification.

This invention relates to devices for constructing breakwater walls under water by utilizing reinforced concrete hollow blocks, and aims to provide certain improvements therein.

Heretofore it has been common to construct breakwater walls surrounded by coffer dams and by pumping the water therefrom and by laying mass concrete in place usually to a height above the water surface.

My invention provides improvements especially applicable to devices of this general character, and in its preferred form it utilizes specially prepared reinforced concrete hollow blocks molded on the shore, floated to their designed location in the wall, and lowered into position on a base prepared for the wall. My invention also includes means for bracing and wedging these blocks into a secure position so as to resist the wave action of the water and also includes means for filling the cavities in the wall with a heavy material such as broken stone or coarse gravel.

In the accompanying drawings which show certain adaptations of my invention, Figure 1 is a vertical cross section taken substantially on the line 2—2 of Figure 2 showing the preferred form of my invention. Figure 2 is a plan of a portion of the same form thereof. Figure 3 is a detail 40 sectional view showing the beveled upper edges. Figure 4 is an elevation of the closed end of one of the header blocks.

Referring to the drawings A and B indicate the reinforced concrete flat slab foundation caps. C the combination keystone and foundation slab of reinforced concrete. D and E the lower reinforced concrete hollow wedges, F and G the upper reinforced concrete hollow wedges, H represents pile timbers sawed off to a grade preferably at the ground surface, J represents the water surface and K the bottom line of the lake or natural ground line.

Referring to the drawings I will now 55 describe in detail the preferred form of my

invention in the adaptation therein illustrated.

The pile timbers H, H, are driven to a firm foundation and the spacing of side piles is such as to form a firm foundation for 60 the wall support. The spacing is not limited, however, to a fixed distance and is dependent on the kind of earth or rock encountered. The line of piles furthest from the shore line may be driven close up or 65 with engaging surfaces so as to prevent a wash of material below the bottom of the wall.

The cap slabs A and B are preferably rectangular concrete blocks reinforced with 70 steel bars and rest flat on the piling sawed to grade, said flat slabs are designed to support the outer ends of the lower concrete units D and E. The member C is preferably a T shaped keystone. It also rests on the prepared piling H H H and is centered to the cross section of the wall. It is designed to support the inner ends of the lower concrete members D and E. This T shaped member also serves as a footing for 75 the wedge shaped concrete members D, E, F and G.

The concrete members D and E are preferably hollow concrete blocks reinforced 80 with steel bars. They are shown shaped as sectors of a cylinder with stubbed apices, and with the flat side resting on the foundation slabs A B and on the key members C.

The members F and G are also hollow concrete blocks reinforced with steel rods. 85 They are also shown shaped as sectors of a cylinder with stubbed ends or apices, and are nested between the lower members D and E and the key member C. The four wedge-shaped members D, E, F and G nesting together form a semi-circle in cross 90 sectional view.

In order to form a further bond in the construction of the wall, I have provided a series of openings, L L in the top and sides 100 of the wedge-shaped hollow blocks, said openings being shown spaced at convenient intervals. These openings are designed to be used for material such as broken stone filling, whereby the complete cavity in each unit concrete hollow block can be closed and this broken stone filling may be subsequently cemented by grout mortar poured into the voids thereof. In this way the concrete units may be bonded together, adding 105 110

strength and weight, so as to make a homogeneous breakwater-wall continuous throughout.

When desired, header blocks may be placed in the construction end of the wall so as to prevent the overflow of grout and broken stone filling.

In order to form close joints and in the upper surface of the wall, the engaging surfaces *a*, *a*, and *b*, *b*, are preferably bevelled-edged, so that the upper edges of the forward concrete blocks may engage closely with the foregoing numbers.

A paved beach in connection with the breakwater wall is represented by *M* and the back filling in the land side of the wall is represented by *N*.

What I claim is:

1. In break-water wall construction, a submerged wall consisting of individual units placed in superposed relation, the lower units of said wall being supporting members for a series of wedge-shaped hollow concrete blocks, keying into each other so as to form an arch upper surface, openings in said hollow blocks through which the blocks may be filled with foreign matter subsequent to the positioning of said blocks in place.
2. A wall construction composed of a plurality of reinforced concrete hollow wedge-shaped blocks, each block having two flat radial sides and a segmentory cylindrical

side, juxtaposed so as to form a sector of a cylinder, a reinforced concrete T-shaped key-block adapted to be interposed between the adjacent sides of the intermediate hollow blocks, and a reinforced concrete supporting block for the outer ends of the lower hollow blocks, all of said blocks being nested together to form a continuous wall substantially semi-circular in cross section.

3. In a wall construction, a plurality of precast hollow blocks wedge-shaped in cross-section arranged in lateral abutting relation with the apices of the blocks disposed downwardly, the tops of the intermediate blocks and the abutting sides of all of the blocks being formed to permit the subsequent introduction of filling material from the top of the wall.

4. In a wall construction, a plurality of pre-cast, wedge-shaped hollow blocks adapted to be arranged in superposed relation, a pre-cast key-block, having sloping sides correlated to the sloping sides of the hollow blocks, disposed intermediate of the adjacent sides of the intermediate blocks, said key-block being provided with an extended base on opposite sides to support the lower hollow blocks.

JOHN P. BALL.
